RAILWAY CAR COUPLER

Rudolf Lorenz and Heinrich Egen, Essen, Germany, assignors to Fried. Krupp Aktiengesellschaft, Essen, Germany, a Corporation of Germany

Application March 15, 1932, Serial No. 598,900,
and in Germany May 1, 1931

10 Claims. (Cl. 213—12)

This invention relates to railway car couplers. In long railway trains, it sometimes happens that upon sudden braking, the brakes of the forward cars in the train act more quickly than the 5 brakes of the cars in the rear part of the train, thereby causing the cars in the rear section to bump violently into each other. In such cases, there arise inertia forces in the cars acting transversely of the direction of the track, which forces 10 may be due for example, to non-uniform loading of the cars and which tend to displace the cars transversely of the direction of the track.

An object of this invention is to provide the 15 couplers with means for clamping the couplers to prevent turning movement thereof under the conditions above described and thereby oppose the tendency of the cars to be displaced under such conditions.

Other objects, novel features and advantages of 20 this invention will be apparent from the following specification and accompanying drawings, wherein:

Fig. 1 is a vertical section through one embodiment of the invention;

Fig. 2 is a section on the line 2—2 of Fig. 1;
Fig. 3 is a section on the line 3—3 of Fig. 1;

Fig. 4 is a view similar to Fig. 1, but with the clamping means in operative position;

Figs. 5 and 6 are views similar to Fig. 1 of modified forms of the invention, and

Fig. 7 is a diagrammatic view.

Referring now more especially to Figs. 1 to 4 inclusive, A is a coupler rod having arms a^1 which lie on opposite sides of a bar B and a pivot pin C passes through the arms and the bar to pivotally connect the rod A to the bar B. The bar B is provided with trunnions b^1 which journal the bar between plates E slidably mounted in guides d^1 supported by the longitudinal beams D attached to the car body. The arms a^1 of the rod A are provided with lugs a^2 and a^3 formed at their ends with bearing eyes a^3 and a^4 . A pin is arranged in the eyes a^4 and supports a lever F having its free end slotted and offset from the main portion of the lever. A second pin is arranged in the eyes a^5 and supports a lever G which lies in the slotted end of the lever F. A pin f^1 connects the offset end of the lever F to the lever G, thereby forming linkage effective to move the arms a^1 toward and away from each other upon swinging movement of the lever G. The arrangement of the levers is such that when the lever G is moved clockwise from the position shown in Fig. 1, the arms a^1 are pulled toward each other into clamping relation 55 to the bar B, thereby preventing horizontal swing-

ing of the rod A. Two yokes H and J are secured to the beams D, the horizontal portions of the yokes being at different elevations. One rod K of a continuous draft gear (not shown) is connected to the plates E.

During normal operation, the elements of the device are in the position shown in Figs. 1 to 3 inclusive, and the arms a^1 bear such relation to the bar B that the coupling rod A is free to swing horizontally. However, if the rod A receives a heavy thrust, it moves to the right against the action of the springs of the continuous draft gear, thereby bringing the lever G into engagement with the yoke J. The lever G is thereby moved clockwise into the position shown in Fig. 4. Such movement of the lever draws the arms a^1 toward each other into clamping relation to the bar B, thereby preventing horizontal swinging of the moving rod A. Accordingly, the couplers are locked to oppose the tendency of the cars to be displaced into the relation exaggeratedly shown in Fig. 7, which relation the cars would tend to assume if not equipped with the clamping means above described. Upon cessation of the thrust, the springs of the draft gear will return the rod A to its original position and the lever G will be turned counterclockwise to its original position, thereby releasing the clamping engagement between the arms a^1 and the bar B and the coupling rod A is again free to swing horizontally.

In the embodiments disclosed in Figs. 5 and 6, the force for clamping the rod A to the cross bar is obtained from the air brake system. In Fig. 5, the lever G is connected by means of a link L with a piston M mounted in an air cylinder N carried by the plates E. The cylinder N is connected through a conduit O with the air system. A spring P tends to maintain the piston M in the position shown in Fig. 5 in which position the linkage is in its inoperative position and the coupler is free to swing. Introduction of air into the cylinder through the conduit O causes the piston M to move to the left, thereby moving the linkage into operative position and bringing the arms a^1 into clamping engagement with the bar B. The conduit O is connected to the line leading from the air reservoir of the car to the brake cylinder. Compressed air flowing from the air reservoir to the brake cylinder actuates the piston N to operate the linkage and clamp the arms a^1 against the bar B. The couplers are thus clamped in good time to enable them to oppose any tendency of the cars to be displaced laterally of the track.

In the modification disclosed in Fig. 6, the arrangement differs from that disclosed in Fig. 5 merely in the mounting of the cylinder N. In this embodiment, the cylinder is carried at the inner end of the plates E, thus making it possible to obviate the necessity of any special stuffing box for the piston rod. The piston is provided with a tubular member which surrounds the piston stem and extends through one end of the cylinder, this member also serving as a support for the spring P.

In this figure, as well as in Fig. 5, the piston M is slightly removed from its limit position so that it is capable of sliding movement to permit vertical oscillation of the coupler without actuating the toggle.

It is evident that various modifications may be made in the device above described, without in any way departing from the spirit of the invention.

We claim

1. In combination with a car frame, a bar slidably mounted thereon, a coupler pivotally attached thereto, and means to clamp said coupler to said bar to prevent swinging movement thereof.
2. In combination with a car frame, a bar, a coupler having arms between which said bar is arranged, a pin pivotally connecting said arms and bar, and means for drawing said arms into clamping relation to the bar to prevent swinging movement of the coupler.
3. In combination with a car frame, a slide supported thereby, a coupler pivoted to said slide, and means effective upon inward movement of the slide to lock said coupler against oscillation.
4. In combination with a car frame, a slide having a cross bar, a coupler having arms between which said cross bar is arranged, a pin pivotally connected to said arms and bar, and means effective upon inward movement of the slide to draw said arms together into clamping relation to said bar to prevent oscillation of the coupler.
5. In combination with a car frame, a slide having a cross bar, a coupler having arms between which said cross bar is arranged, a pin pivotally connecting said arms and bar, levers pivoted to said arms and to each other for draw-

50

ing said arms into clamping relation to said bar, and means for actuating said levers.

6. In combination with a car frame, a slide having a cross bar, a coupler having arms between which said cross bar is arranged, a pin pivotally connecting said arms and bar, levers pivoted to said arms and to each other for drawing said arms into clamping relation to said bar, and means on said car frame for operating said levers upon movement of the slide relative to the car frame.

7. In combination with a car frame, a cross bar, a coupler having arms between which said cross bar is arranged, a pin pivotally connecting said arms and bar, levers pivoted to said arms and to each other to form linkage effective upon actuation of one of said levers to draw the arms into clamping relation to said bar, and means for actuating said lever.

8. In combination with a car frame, a cross bar, a coupler having arms between which said cross bar is arranged, a pin pivotally connecting said arms and bar, levers pivoted to said arms and to each other to form linkage effective upon actuation of one of said levers to draw the arms into clamping relation to said bar, and pneumatic means for actuating said lever.

9. In combination with a car frame, a slide having a cross bar, a coupler having arms between which said cross bar is arranged, a pin pivotally connecting said arms and bar, levers pivoted to said arms and to each other to form linkage effective upon actuation of one lever to draw said arms into clamping relation to said bar, and means on said car frame to engage said lever to operate said linkage upon movement of the slide relative to the car frame.

10. In combination with a car frame, a slide having a cross bar, a coupler having arms between which said cross bar is arranged, a pin pivotally connecting said arms and bar, levers pivoted to said arms and to each other to form linkage effective upon actuation of one lever to draw said arms into clamping relation to said bar, and pneumatic means for actuating said lever.
